(57) **CLAIM**

The ornamental design for a vehicle tail light lens, as shown and described.

DESCRIPTION

FIG. 1 is a frontal perspective view of a left vehicle tail light lens attached to a vehicle, no part of the vehicle is claimed; FIG. 2 is a left perspective view of the left vehicle tail light lens;

FIG. 3 is a front elevation view of the left vehicle tail light lens;

FIG. 4 is a left side elevation view of the left vehicle tail light lens;

FIG. 5 is a top plan view of the left vehicle tail light lens;

FIG. 6 is a bottom plan view of the left vehicle tail light lens;

FIG. 7 is a right side elevation view of the left vehicle tail light lens;

FIG. 8 is a frontal perspective view of an alternative embodiment of the taillight lens illustrated in FIGS. 1-7, showing a right vehicle tail light lens attached to a vehicle, no part of the vehicle is claimed;

FIG. 9 is a perspective view of the right vehicle tail light lens;

FIG. 10 is a front elevation view of the right vehicle tail light lens;

FIG. 11 is a right side elevation view of the right vehicle tail light lens;

FIG. 12 is a top plan view of the right vehicle tail light lens;

FIG. 13 is a bottom plan view of the right vehicle tail light lens; and,

FIG. 14 is a left side elevation view of the right vehicle tail light lens.

The phantom lines are not a part of the claimed invention.

1 Claim, 14 Drawing Sheets
